UNITED STATES PATENT OFFICE

GEORGE R. HARVEY, OF LA FAYETTE, INDIANA

COMBINATION RAZOR AND SHAVING BRUSH

Application filed April 29, 1932. Serial No. 608,303.

The present invention relates to shaving devices and has for one of its objects to provide a unitary construction including all of the essentials of a shaving outfit.

5 A further object of the invention resides in combining with a conventional safety razor a self-feeding brush so disposed with respect to the cutting edge of the blade as to apply the shaving material to the face of the user in advance of the razor.

10 Another object of the invention consists in providing a multiple tool as above-mentioned in which the emollient for the face will have a free and unobstructed path along 15 which it may readily be fed to the bristles of the brush.

15 A still further object of the invention resides in the general arrangement and assemblage of parts to facilitate both the manufacture and use of the combined device.

20 Other objects and advantages of the invention will be apparent from the following description when taken in connection with the accompanying drawing, in which,

25 Figure 1 is a perspective view of the combination device.

Figure 2 is a longitudinal sectional view.

30 Figure 3 is a fragmentary plan view of that portion of the device including the brush, with the bristles removed for the sake of clearness, and,

35 Figure 4 is a sectional view taken on the line 4—4 partly broken away.

Referring to the drawing in more detail, 40 numeral 1 indicates any preferred type of safety razor mounted on a threaded boss 2. The handle of the razor in the present form of the invention consists of a hollow tube 3 into which the boss 2 is threaded and in order that the razor may always assume the same position with respect to the handle 3, a shoulder 4 is provided against which the boss 2 engages.

45 Formed on that side of the holder 3 on which the cutting edge of the blade is situated is a compartment or chamber 5, which extends transversely of the handle and communicates with the interior thereof through the passageway 6. The longitudinal walls 50 of the compartment 5 are bent adjacent their

outer edges to provide guideways 7 for a brush-head 8, provided with bristles 9 secured in any conventional manner.

The brush-head 8 is held in the guideways 7 against accidental removal by snap fasteners, or the like, comprising indentations 10 adjacent the closed ends of the slots and protuberances 11, formed on the head and adapted to snap into the indentations 10. The opposite end of the brush-head 8 is provided with a finger grip 12 for withdrawing the head from its holder and also for forcing the same into locking engagement with the snaps 10.

55 The hollow handle 3 is adapted to receive a shaving cream or other emollient, and in order to feed the same to the brush 9, the head 8 is provided with a plurality of feed slots 13. The emollient is forced from the handle 3 into the compartment 5 by means of a plunger 14, provided with a threaded end 15 adapted to cooperate with threads 16 formed on the inner wall of the handle or emollient reservoir.

60 The hollow handle 3 is adapted to receive a shaving cream or other emollient, and in order to feed the same to the brush 9, the head 8 is provided with a plurality of feed slots 13. The emollient is forced from the handle 3 into the compartment 5 by means of a plunger 14, provided with a threaded end 15 adapted to cooperate with threads 16 formed on the inner wall of the handle or emollient reservoir.

65 It will be noted that the inner end of the boss 2 is provided with an arcuate baffle 17. This baffle serves as a guide to direct the material through the passage 6 into the compartment 5, and it will also be noted that the bottom of the compartment 5 is tapered 70 towards the ends of the brush-head, as indicated by the numeral 18, thereby avoiding any sharp angles which might tend to cause an accumulation of unused paste.

75 The plunger 14, which serves to discharge the material from the reservoir 3, is preferably hollow and is closed at its outer end by a plug stopper 19, in which may be mounted a styptic pencil or other desired instrument.

80 In the operation of the device the compartment 3 being charged with a soap or other emollient, the brush 9 is first dampened and the plunger 14 is then rotated so as to cause the desired amount of the material to be discharged through the slots 13 onto the tufts of the brush. The instrument is then drawn over the face of the user so as to cause the brush to travel in advance of the cutting edge 85 of the blade, the brush applying the material 90 to the face.

to the face and the razor then performing its function in a manner which will be readily understood. In the event that a soap is employed in the device in lieu of a shaving cream the brush may be operated in a well-known manner to create a lather prior to bringing the razor itself into use.

From the foregoing description taken in connection with the accompanying drawing, 10 it will be seen that I have devised a unitary construction involving all of the essentials of a shaving outfit; that the self-feeding brush is so located as to adapt it to apply a shaving cream to the face at the proper distance in advance of the cutting edge of the 15 razor blade; that the brush is also adapted as to be so operated as to create a lather in the event that soap is employed, and that the feeding system is so designed as to avoid 20 any dead or stagnant spots and to permit a free passage of the material to the tufts of the brush.

In accordance with the patent statutes I have described what I now believe to be the 25 preferred embodiment of the invention, but since it is obvious that various minor modifications may be made in the details of construction without departing from the spirit of the invention, it is intended that all such 30 modifications be included in the scope of the appended claims.

What I claim is:

1. A combination shaving outfit, including 35 a safety razor provided with a hollow handle, a brush having a hollow portion in communication with the hollow handle and disposed in advance of the cutting edge of the blade, and means for forcing an emollient onto the bristles of the brush.

40 2. A combination shaving outfit, including a safety razor provided with a hollow handle, a brush having a removable head provided with slots for communication with the interior of the handle, said brush being disposed slightly in advance of the cutting edge 45 of the blade, and means for forcing an emollient onto the bristles of the brush.

3. A combination shaving outfit, including 50 a safety razor provided with a hollow handle, an elongated chamber secured to the hollow handle adjacent the cutting edge of the blade and in communication with the interior of the handle, a slotted brush head slidably mounted on the top of the chamber, and 55 means for forcing an emollient onto the bristles of the brush.

4. A combination shaving outfit, including 60 a safety razor provided with a hollow handle, an elongated chamber secured to the hollow handle adjacent the cutting edge of the blade and in communication with the interior of the handle, a slotted brush head slidably connected to the top of the chamber, a snap fastener for securing the brush head in 65 position, and means for forcing an emollient

through the handle onto the bristles of the brush.

5. A combination shaving outfit, including 70 a safety razor provided with a hollow handle, an elongated chamber secured to the hollow handle adjacent the cutting edge of the blade and in communication with the interior of the handle, a curved baffle in the handle for directing a flow of material from the handle into the chamber, a brush head connected to 75 the top of the chamber, and means for forcing an emollient through the handle onto the bristles of the brush.
